DETACHABLE EXTENSION TABLE TOP

Alfreda E. Graves, 1434 SW. 158th, Seattle 66, Wash.

Filed Oct. 16, 1958; Ser. No. 767,567

3 Claims. (Cl. 311—41)

This invention relates to extension tables, and namely that type of table in which the top includes a center or nave section of comparatively small area and has several leaf sections removably associated therewith, the addition of such leaves giving to the assembly a greater areal compass when the need or desire therefor arises.

It is one object of the invention to provide a table of sturdy construction and unusually attractive appearance having removable leaf sections for the sides and for the ends so as to be extensible both transversely and longitudinally, and characterized in that the leaves rest upon rails slidably supported for movement into and from operating positions. As a further object still the invention aims to provide an extension table of the character described in which the rails so interfit with the leaves as to preclude shifting of the leaves relative to the main or nave section of the table.

A further important object is to provide an extension table in which only the rails which give support to the side leaf sections find their slide mounting in the nave section of the table, the rails which support the end leaf sections receiving their slide mounting from side leaf sections.

A still further and important object of the invention is to provide an extension table of the character described having the ends of said sliding rails exposed for maximum accessibility, and wherein such exposed ends are fitted with escutcheon plates so blending with the architecture of the table as to give the appearance of being permanently affixed hardware therefor.

The foregoing and other objects and advantages in view will appear and be understood in the course of the following description and claims, the invention consisting in the novel construction and in the adaptation and combination of parts hereinafter described and claimed.

In the accompanying drawings:

Figure 1 is a perspective exploded view portraying the nave section and four removable leaf sections of an extension table constructed to embody the preferred teachings of the present invention.

Fig. 2 is a perspective view of said several sections shown in the positions occupied when the nave section of the table has been extended by the addition of the four leaf sections.

Fig. 3 is a transverse vertical sectional view drawn to an enlarged scale on line 3—3 of Fig. 2.

Fig. 4 is a fragmentary longitudinal vertical sectional view drawn to a yet larger scale on line 4—4 of Fig. 3; and

Fig. 5 is a fragmentary perspective view of the nave section of the table with the leaf sections removed, the view being from the underside looking at the near corner, considered from the vantage point of Fig. 2.

Referring to said drawings the main or nave section of the table is designated by the numeral 10, and is comprised, by preference, of a slab of hardwood having a rectangular plan configuration and sustained by pedestals 11. The pedestals are desirably metal and are fixedly

2

secured to such nave section so as to underlie the same in positions spaced from but proximate to the two end extremities. From the standpoint of appearance the slab should be fairly thick and have a length considerably longer than its width, say 5' x 2'. The leaf sections for the present table are also rectangular in plan configuration and are desirably cut from a hardwood stock of the same thickness. There are six leaf sections, two of which are side leaves designated by 12 and the other four are end leaves designated by 13. As will be clear from the following description, the length of the side leaf sections is dictated by the length of the nave section. The width of the nave section aggregated with that of the two side leaf sections determines the length of the end leaf sections. By such token, and assuming that the leaf sections have a width of 9", the side leaf sections are 9" x 60" while the end leaf sections are 9" x 42". It is self-evident that additional end leaf sections may be employed if desired, each grooved in correspondence with the grooving of the sections 13.

At each end of the nave section in the space between the related pedestal and the end extremity there is carried a respective pair of rails, as 14 and 15, mounted for transverse slide movement. These rails lie one alongside the other and each has a rather snug fit in a respective slide-way 16 so routed from the underside of the nave section that one such slide-way is exposed to one side edge of the nave section and the other slide-way to the other side edge. Each rail rides upon two cross-bars 17 spaced apart longitudinally of the slide-way and secured in position by screws or the like 18. The rails are metal, as are the cross-bars, and have an exposed end of each secured to a respective escutcheon head 20.

When the outer ends of the rails are withdrawn from the related slide-ways there is provided at each side of the nave section a substantial cantilever shelf on which the side leaf sections 12 are adapted to rest, and each said side leaf section has transverse grooves 21 routed from its underside to receive the related rails. The grooves 21 exactly register with the slide-ways 16, wherefore ends of the rail-supported side leaf sections lie flush with the ends of the nave section.

A slide-way 22 is routed from the underside of each side rail section at each end thereof on the approximate longitudinal median line of the section, with each said slide-way exceeding the depth of the grooves 21 by the thickness of a rail. A rail, as 23 and 24, is received in each slide-way and, like the rails 14 and 15, derives support from a pair of cross-bars 27 spaced apart longitudinally of the concerned slide-way. Counterparts 25 of the escutcheon heads 20 are secured upon the ends of the rails 23 and 24 exposed in the slide-ways 22. A withdrawal of the outer ends of the rails 23 and 24 produces a shelf, acting in this instance to support the end leaf sections 13. As with the side leaf sections, grooves 26 are routed in the underside of the end leaf sections to receive the protruding ends of the rails 23 and 24, these grooves exactly registering with the slide-ways 22.

For attaching the escutcheon heads to the rails the latter are mortised into the heads and are fixedly secured by a respective cap screw 30. The heads each present a planar back face 28 which extends horizontally well beyond both side edges, and vertically well beyond both the upper and the lower edge, of the related rail. The bottom projection projects a lip, as 29, readily engageable by a finger for withdrawing the rails when it is desired to extend the same for reception of the leaves. When pushed inwardly to the maximum of the permitted travel each escutcheon head lies flat against a side edge of the nave section or a leaf section, as the case may be, and gives to such head every appearance

of being fixedly secured to the concerned section as ornamental hardware therefor. The effect—American Primitive—is perform enhanced either by the employment of thick slab stock, as shown, or by the use of plywood with a finish skirting of sufficient depth and the proper graining to suggest slab stock. Hardware can be easily designed to provide slide-ways upon the underside of plywood panels, in lieu of routing slab stock in the manner here shown and described.

It will be apparent that the table can be used either with the nave section alone, the nave section and one or both side leaf sections, or the nave section, side sections, and one or both end leaf sections, providing in every such instance an extremely attractive and sturdy table and one in which the addition or removal of the leaf sections can be easily and quickly accomplished.

It is thought that the invention will have been clearly understood from the foregoing detailed description of my now preferred illustrated embodiment. Changes in the details of construction will suggest themselves and it is accordingly my intention that no limitations be implied and that the hereto annexed claims be given a scope fully commensurate with the broadest interpretation to which the employed language fairly admits.

What I claim is:

1. An extension table comprising a main nave section of rectangular plan configuration providing transversely extending slide-ways upon its underside each open by one end thereof to a side edge of the section, there being at least two of said slide-ways for each side edge spaced one from the other longitudinally of the section, a respective rail received in each slide-way for movement between two extremes in one of which the rail is wholly housed within the slide-way and in the other of which a substantial portion of the rail projects as a cantilever beyond the related side edge, and side leaf sections of rectangular plan configuration corresponding in length to the length of the nave section and in width to a permitted projection of said rails and provided upon their underside with full-width grooves placed so as to register with the slide-ways and arranged to receive the projecting ends of said rails for localizing the leaf sections relative to the nave section, the cantilever portion of each of said rails being provided upon its extremity with an escutcheon head brought to bear upon the related side edge of the nave section when the rail is retracted and upon the outside edge of a sustained side leaf section when the rail is extended, concealing the rail and its slide-way or its groove, as the case may be, and giving to the escutcheon head the appearance of being a fixed piece of ornamental hardware for the table.

2. An extension table comprising a main nave section of rectangular plan configuration providing transversely extending slide-ways upon its underside each open by one end thereof to a side edge of the section, there being at least two of said slide-ways for each side edge spaced one from the other longitudinally of the section a respective rail received in each slide-way for movement between two extremes in one of which the rail is wholly housed within the slide-way and in the other of which a substantial portion of the rail projects as a cantilever beyond the related side edge, side leaf sections of rectangular plan configuration corresponding in length to the

length of the nave section and in width to a permitted projection of said rails and provided upon their underside with full-width grooves placed so as to register with the slide-ways and arranged to receive the projecting ends of said rails for localizing the leaf sections relative to the nave section, said side leaf sections each providing at least two longitudinally extending slide-ways upon its underside open by an end of each one to one and the other to the other end edge of the section, a respective rail received in each of said last-named slide-ways for movement between two extremes in one of which the rail is wholly housed within the slide-way and in the other of which a substantial portion of the rail projects as a cantilever beyond said open end, and end leaf sections of rectangular plan configuration corresponding in length to the aggregate width of the nave and the side leaf sections and in width to a permitted projection of said rails and provided upon their underside with full-width grooves arranged to receive the projecting ends of said rails and placed so as to register with the slide-ways of the side leaf sections when said side leaf sections are in their rail-sustained operating positions at opposite sides of the nave section, the rails which sustain the side leaf sections occupying a level below that of the rails which sustain the end leaf sections, the cantilever portion of each of said first-named rails being provided upon its extremity with an escutcheon head brought to bear against the related side edge of the nave section when the rail is retracted and against the outside edge of a sustained side leaf section when the rail is extended, the cantilever portion of each of said second-named rails being likewise provided upon its extremity with an escutcheon head brought to bear, when the rail is retracted, against the related side edge of the side leaf section by which it is slidably carried and, when the rail is extended, against the outside edge of a sustained side leaf section, all of said escutcheon heads being identical and being characterized in that the same perform a holding function as well as concealing the rail and its slide-way or its groove, as the case may be, and giving to the escutcheon head the appearance of being a fixed piece of ornamental hardware for the table.

3. Structure as recited in claim 1 in which the side leaf sections lie flush with the nave section, both top and bottom, when applied to said nave section, and wherein at least the said edges of the sections have considerable depth so that the table top gives the appearance of thick slab stock, the relationship as between such rails and the said nave and side leaf sections being such that the undersides of the rails occupy a level no lower than the bottom limit of said side and end edges of the table sections.
